ELECTRON LENS

Otto Ernst Heinrich Klemperer, Iver, England, assignor to Electric and Musical Industries, Ltd., a British corporation

Application March 31, 1944, Serial No. 528,994
In Great Britain April 8, 1942

13 Claims. (Cl. 250—160)

1

The present invention relates to electrode systems for producing electron lenses such as are employed in cathode ray tubes, electron discharge valves and other electron discharge devices for focusing electron beams and to electron discharge devices including such systems.

An electrode system for producing an electron lens is usually disposed symmetrically about an axis and affords a passage through which the beam to be acted on is projected. For example, the electrode system may comprise two axially aligned plane diaphragm electrodes having central apertures defining said passage or tubular electrodes embracing said passage with their ends or transverse edges included in planes perpendicular to the axis. Thus, Figures 1A and 1B of the accompanying drawing are each diagrammatic side elevational views of known systems of tubular electrodes, each comprising two aligned tubular electrodes A and B respectively, through which the beam to be acted upon is projected. With such systems, if electrodes A and B are maintained at different potentials V_1 , V_2 , respectively, the electron lens so produced will be converging whichever electrode is the more positive and whether or not an electron beam is projected from left to right or from right to left through the system. The focal length of the lens will depend on the ratio of the voltages applied to the electrodes A and B with respect to the cathode of the beam operated upon. As illustrated in Figure 1A, electrodes A and B may be of the same diameter so that the edges of the electrodes are in registry, the electrodes being separated by a gap G having an axial length sufficient to provide an adequate insulation between the two electrodes. In this case the electron lens is constituted by the electrostatic field produced about the gap G and the mid-surface of the lens, which is an arbitrarily selected surface of reference located in the manner described, for example, in the Cambridge Physical Tract "Electron optics" by O. Klemperer, Cambridge University Press, 1939, is constituted by the surface midway between the surfaces including the inner edges of electrodes A and B, namely the edges of the electrodes A and B on either side of the gap G. As these surfaces are plane the mid-surface is a plane and is indicated by the chain dotted straight line M of Figure 1A. If the electrodes A and B are of different diameters they are preferably disposed with the end of one electrode inserted within the other as electrode illustrated in Figure 1B. In this case the lens is constituted by the electrostatic field produced about the end

2

of the smaller diameter electrode (A in Figure 1B) embraced by the larger diameter electrode (B in Figure 1B), and the mid-surface of the lens is defined as the surface including the inner edge or edges of the aforesaid end of the smaller diameter electrodes. Thus, in the case shown in Figure 1B the mid-surface of the lens is constituted by the plane of the aforesaid end of the smaller diameter electrode, this plane being represented by the line M in Figure 1B. The electrodes A and B may be of circular, rectangular, square, elliptical or other desired cross-section having axial symmetry, or they may each comprise a pair of oppositely disposed elements, for example of plate form.

In the case of an electron lens system comprising a pair of diaphragm electrodes the mid-surface of the lens is defined, as the surface midway between the facing surfaces of the diaphragm electrodes. Thus, in the case of the hitherto known arrangements including plane diaphragms the mid-surface is again also a plane.

In cases where the electrode system comprises more than two electrodes the field produced is equivalent to that of several pairs in combination, and the system may be treated as producing a combination of separate lenses each constituted between one electrode and the next in succession along the axis. In the case of a system comprising three electrodes for forming a saddle field lens, the mid-surface may be defined as the surface midway between the surfaces including the inner edges or facing surfaces as the case may be of the outermost electrodes, but the arrangement can also be regarded as composed of a pair of lenses constituted by the electrostatic fields in the gaps between the electrodes.

As far as I am aware, in the prior construction of electron lens systems employing only electrodes which afford an unobstructed passage for the beam to be acted upon, such as tubular or diaphragm electrodes or combinations of tubular or diaphragm electrodes, the edges of lens-forming tubular electrodes in the lens field, herein referred to as the "inner edges," or the facing surfaces of the lens-forming electrodes have been bounded by planes and consequently the mid-surfaces of the lenses have been planes. I am aware, however, that electrode systems for forming electron lenses have been proposed including curved electrically conducting mesh elements disposed across the path of the beam to be acted on, and in some such constructions the mesh elements have been so curved that the electron lenses obtained would have curved mid-surfaces.

However, electrode systems employing mesh elements have the disadvantages that the mesh elements intercept electrons in the beam and it is difficult to obtain satisfactory focusing. Moreover, as far as I am aware, the advantages to be obtained by employing lenses with curved mid-surfaces have never been appreciated.

The present invention arises out of an investigation for the purpose of providing improved electrode systems for producing electron lenses for focusing an electron beam in a line, for example as required in certain kinds of electron discharge valves for high frequency operation, for example, in devices of the kind known as Klystrons.

According to one feature of the present invention an electrode system for forming an electron lens is provided comprising two aligned co-operating electrodes affording an unobstructed passage for an electron beam to be acted upon, and having the inner edge or edges of each electrode presented to the inner edge or edges of the other, said edge or edges being so curved that the mid-plane of said lens is curved.

According to another feature of the present invention an electrode system for forming an electron lens is provided comprising two aligned co-operating electrodes affording an unobstructed passage for an electron beam and of which one electrode is of smaller diameter than the other and has one end inserted within the other, the edge of said end being so curved that the mid-plane of said lens is curved.

According to a further feature of the present invention an electrode system for forming an electron lens is provided comprising a pair of apertured diaphragm electrodes disposed with their apertures aligned to afford an unobstructed passage for an electron beam, said electrodes having their facing surfaces so curved that the mid-plane of said lens is curved.

The invention also includes electron discharge apparatus having an electrode system as above set forth and means for projecting an electron beam through said passage and means for maintaining the electrodes of said system at such potentials that said beam is acted upon in a desired manner.

Among the objects of the invention are to provide an improved method of and means for focusing an electron beam.

Another object is to provide an improved method of and means for reducing aberration in an electron lens.

A further object is to provide an improved method of and means for deriving a line image of an electron source.

An additional object of the invention is to provide an improved electron lens having a curved mid-plane to reduce spherical aberration.

Another object is to provide an improved method of and means for focusing an electron beam by employing an electron lens system in which the component electron lenses have curved mid-planes.

In order that the said invention may be clearly understood and readily carried into effect the same will now be described with reference to Figures 2 to 10 of the accompanying drawing, of which

Figure 2 is a perspective view of an electrode system according to the invention,

Figure 3 is a perspective view of an electrode for use in a further electrode system according to the invention,

Figures 4A and 4B are plan and elevational views respectively of an electrode system according to the invention including cylindrical electrodes,

5 Figure 4C is a perspective view of one of the electrodes shown in Figures 4A and 4B,

Figure 4D is a plane development of the electrode of Figure 4C,

10 Figures 5A and 5B are a perspective view and a plane development respectively of a further electrode of cylindrical cross-section for use in a system according to the invention,

15 Figures 6 and 7 show two electrode systems formed in accordance with the invention, and each of which comprises two tubular electrodes, one of which is of smaller diameter than the other and has one end inserted within the other electrode in the manner described with reference to Figure 1B above,

20 Figure 8 illustrates a construction of an electrode for use in the system in accordance with the invention of which the lens-forming elements are of diaphragm form, and

25 Figures 9 and 10 show two electrode systems formed in accordance with the invention and each including more than two lens-forming electrodes.

30 In Figure 2 of the drawing an electrode system is shown which is suitable for focusing an electron beam at a line perpendicular to the axis of the system. Such a system may be employed, for example, for focusing a flat ribbon-shaped beam.

35 The system shown in Figure 2 comprises a pair of electrodes A and B aligned and having their sides in registry and affording a passage of uniform rectangular cross-section throughout their length. The electrodes are separated by a gap G to isolate them electrically from one another. The electrode A has horizontal sides 1 and 2 and vertical sides 3 and 4, while the electrode B has horizontal sides 5 and 6 and vertical sides 7 and 8. The horizontal sides of the electrodes A and B are represented as being wider than the vertical sides, but for some applications, the sides may 40 all be of the same width so that the cross-section of the electrodes is square or the vertical sides may be wider than the horizontal sides.

45 If the electrodes A and B are maintained at different potentials, the electron lens produced is analogous to two crossed cylindrical optical lenses, one lens corresponding in effect to the field due to the sides 1, 2 and 5, 6 of the electrodes A and B and serving to focus a projected electron beam at a line in the horizontal plane through the axis of the system, and the other lens corresponding in effect to the field due to the narrow sides 3, 4 and 7, 8 of the electrodes A and B and tending to focus the beam at a line in the vertical plane through the aforesaid axis.

50 In accordance with the present invention, the inner ends of the vertical sides 3, 4 and 7, 8 of the electrodes A and B are formed with curved edges to constitute an electron lens having a curved mid-surface. Thus, in the example ill-

55 lustrated in Figure 2 the curved edges are cut to conform to cylindrical surfaces of radius R having their axes perpendicular to the axis of the electrode system, the curved edges on electrode A being recessed and the curved edges on electrode B being convex and complementary to those of electrode A. The mid-surface of the electron lens will then be a cylindrical surface of radius R located in the middle of the gap G.

60 Such a system is found to give better focusing 65 of a beam of given cross-section than a system 70 of a beam of given cross-section than a system 75

having all the inner edges straight and will handle satisfactorily a beam filling a greater part of the cross section of the electrode system. For best results, the radius R is preferably made small, for example, it may be made half the width of the vertical sides of the electrodes A and B so that the edges thereof are semicircular. Besides improving the focusing properties of the lens, the curvature of the mid-surface also controls to some extent the focal length of the lens.

If the electrode B is maintained at a higher positive potential than the electrode A, a parallel electron beam passing through the lens field will be caused to converge whatever the ratio of the voltages on the electrodes. However, if, in the arrangement of Figure 2, the electrode A is maintained at a more positive potential, the lens field will cause a beam projected through it in either direction to diverge.

As already pointed out, the vertical sides 3, 4 and 7, 8 of the electrodes A and B of Figure 2 have a slight focusing action on an electron beam passing through the electrodes. They also cause the focal line obtained when a flat ribbon-shaped beam is projected through the system to be curved especially in the vicinity of the sides. These difficulties can be avoided by curving the inner edges of the horizontal sides 1, 2 and 5, 6 of electrodes A and B. For example, Figure 3 shows a perspective view of an electrode B' which corresponds to the electrode B of Figures 1 and 2, but which has the edges of its wide sides 5, 6 cut away or recessed to conform to a cylinder of radius R_1 . If the electrode B' is employed with a co-operating electrode similar to the electrode A of Figure 2 but having the inner edges of its horizontal sides such as 1, 2 convexly curved to conform to a cylinder of radius R_1 , then if the value of R_1 is correctly chosen an electron lens may be produced which is effectively the equivalent of a single pair of wide plate form elements corresponding to the sides 1, 2 and 5, 6 of electrodes A and B without the vertical sides 3, 4 and 7, 8, though the vertical sides are still present to shield the path of the beam through the electrodes. The radius R_1 may be made quite small, for example, a simple, but quite effective, construction is afforded by making the edges of the horizontal sides semicircular, the curvature of the edges of the horizontal sides being determined by the width thereof.

In the systems described with reference to Figures 2 and 3 of the drawing the curvature of the mid-surface of the lens is identical with that of the surface in which the curved inner edges of the lens-forming electrodes A and B or A' and B' are located, but it is not essential that this should be so. Thus the curvature of the inner edges of the electrodes may be made to differ so that the curvature of the mid-surface is different from that of the edges of either electrode. For example, if the radii of the registering edges of the electrodes differ by an amount equal to the width of the gap G, the radius of the mid-surface will be equal to the mean of the radii of the adjacent edges. Furthermore, the inner edges of the electrodes A and B need not conform to cylindrical surfaces. For example, in order to correct for aperture error corresponding to spherical aberration in an optical lens, it may be desirable to cause the radius of curvature of the mid-surface to be greater at the center of the lens field about the axis of the

lens forming electrode system than it is on the edges thereof.

Figures 4A to 4D of the drawing illustrate the application of the invention to a system of electrodes in which the electrodes are cylindrical and afford a passage of uniform circular cross-section throughout. This system, like the systems described with reference to Figures 2 and 3 is intended for focusing a ribbon shaped beam to

10 a line.

Referring to Figures 4A and 4B it will be seen that the electrode system shown comprises a pair of electrodes A'' and B'' having their edges formed with diametrically opposed projecting portions 11, 12 or 13, 14 as the case may be, the edges being complementary. The electrodes A'' and B'' are identical in form, the single electrode B'' being shown in Figure 4C and a plane development of this electrode is shown in Figure 4D. From the latter figure it will be seen that the projecting portions 13 and 14 are formed by cutting the edge of the electrode to conform to a series of semicircular arcs 15, 16, 17 and 18 each of radius equal to an eighth of the circumference of the tube, the arcs being alternatively convex and recessed. The electrodes may be formed by severing a single flat sheet of material along the line of the arcs 15 to 18 and rolling the two severed portions of the sheet to provide the electrodes.

The system of Figures 4A and 4B will focus a beam having a diameter equal to the radius R_T of the tubular electrodes at a line without giving rise to any appreciable aberration and with quite small ratios between the voltages on the electrodes. For example, to produce a line focus at a distance of five times the tube radius from the principal plane of the lens system the voltage ratio is only about 1.4 whereas a straight edge two-tube lens requires a voltage ratio of about 40 six to give the same focal length.

However, the length of the focal line may be greater than the original diameter of the beam and the beam may be divergent in directions parallel to the plane, and, in fact, with the construction of electrodes described with reference to Figures 4C and 4D, the divergency of the focused beam is such that the focal line will have a length of the order of twice the diameter of the original beam. If it is desired that the beam shall not be divergent, or should be of different divergency the inner edges of electrodes A'' and B'' can be shaped accordingly. For example, if, instead of cutting the inner edges of the electrodes to conform to semicircular arcs of radius

$$\frac{\pi R_T}{4}$$

(or one eighth the circumference of the tube) as described with reference to Figure 4D, the arcs are not made semi-circular, but are given a radius $2\pi R_T$ approximately, a system which produces practically no divergency of the beam will be produced. The focal length of the system will be increased however, and also the aberration produced. Such behaviour is of course to be expected from the fact that as the radius of the arcs 15 to 18 is increased, the electrodes A'' and B'' become more nearly straight edged. Thus, if the radius is increased indefinitely a system producing a point focus would be obtained. From this it will be appreciated that if the radii of the aforesaid arcs are greater than $2\pi R_T$ the beam will converge after passing through the lens systems there being two real focal lines for the lens dis-

posed at different distances from the mid-surface and in planes at right angles to each other.

In some cases a satisfactory focusing of a ribbon shaped beam may be obtained with complementary cylindrical tubular electrodes formed in the manner illustrated at A''' in Figures 5A and 5B with straight edge portions 21 and 22 alternately with arcuate portions either convex as shown at 23 and 24 in Figures 5A and 5B or concave. However, a lens system formed of electrodes constructed in this manner is not thought to have a very wide application. It is believed that having regard to the description already given with regard to the system of Figures 4A and 4B, the mode of operation of a system employing electrodes formed in the manner indicated with reference to Figures 5A and 5B will be understood without difficulty.

Figures 6 and 7 of the drawing show the application of the invention to lens systems of the kind described above with reference to Figure 1E, in which the lens field is formed at the end of a tubular electrode inserted within another electrode of larger diameter. Thus, in the example shown in Figure 6, the system is constituted by co-operating cylindrical electrodes A'' and C, the electrode A'' having one end formed with projecting portions 11 and 12 in the manner described with reference to Figures 4C and 4D above, and having this end inserted within the larger diameter electrode C, shown partly broken away to show the disposition of parts within its interior. The electrode C may be constituted by a conducting coating on the neck of a cathode ray tube for example. Preferably the electrode A'' of Figure 6 carries a conducting flange 25 for effectively closing the end of electrode C so as to shield the lens field from field penetration through the gap between the electrodes. A suitable gap must be maintained between the flange 25 and the electrode C for insulating purposes. With the arrangement of Figure 6 the lens field obtained is similar in effect to that produced by the system of Figures 4A and 4B, which has been described in detail above.

Figure 7 shows an arrangement similar to that shown in Figure 6 but in which the cylindrical electrode A'' is replaced by an electrode A' of square cross-section, and the inner end of which is formed with semi-circular edges in the manner described with reference to Figure 3 above. The effect of the square section electrode A' is substantially the same as that of a tubular electrode such as A'' of Figure 6 of a diameter equal to the length of the side of the square cross-section, and it will be appreciated that the curvatures of the inner ends of the electrodes A'' and A' of Figures 6 and 7 can be varied in the manner indicated with reference to Figures 4A and 4B above, the lens being diverging or converging or substantially ineffective in planes parallel to the plane of symmetry between the projecting portions of the electrode according to the curvature of the edges of electrode A' or A'' as the case may be.

The construction shown in Figures 6 and 7 are particularly free from errors due to misalignment of the lens forming electrodes and are eminently suitable for use in cathode ray guns. The choice as to whether a cylindrical electrode such as A'' of Figure 6 or a square section electrode such as A' of Figure 7 is employed will depend on which electrode is the more suitable for incorporation in the particular device in which it is employed. Both constructions give lens fields with excellent qualities in respect of freedom from aberration,

the construction of Figure 6 being particularly valuable in this respect.

While in the detailed description above, the application of the invention to lens forming systems including tubular electrodes has been described, the invention may also be applied to systems in which diaphragms are employed as lens forming elements. For example, in Figure 8 of the drawing an electrode D is shown constituting of a rectangular tube 27 constituting a shield portion, the shield portion having one end closed by a diaphragm 28, constituting the lens-forming element, the diaphragm being curved to conform to a cylindrical surface and having a slot 29 extending parallel to its curved edges. This electrode may be arranged to co-operate with a similarly formed electrode but with the end carrying the diaphragm recessed and curved in a manner complementary to the curvature of the end of the electrode D. With such an arrangement, if a flat ribbon-shaped beam is projected axially through the system with its longer dimension in the direction parallel to the edges of the slots such as 29 in the diaphragm, and the electrodes are maintained at different potentials, the beam will be focused at a short line.

In some applications, diaphragms such as 28 might be constituted simply by elements in the form of strips separated by a gap corresponding to the slot 29, and the shield portion 27 might be omitted.

Figures 9 and 10 show the electrode systems for producing a plurality of lenses having mid-surfaces curved in accordance with the invention.

The arrangement of Figure 7 includes three electrodes 30, 31, 32, separated by gaps 33, 34, the two mid-surfaces of which are oppositely curved. The potentials V₁, V₂, V₃, respectively, of the electrodes 30, 31 and 32 may be arranged to increase or decrease successively, or the electrode 31 may be at a more positive or less positive potential than either of the electrodes 30 and 32. If the potential of the electrode 31 is lower than both of the electrodes 30 and 32, a saddle field is produced. In Figure 8 an electrode system is shown comprising five electrodes 35, 36, 37, 38, 39, separated by gaps 40, 41, 42, 43, the electrodes being formed with curved edges in accordance with the invention. In operation the potentials V₁, V₂, V₃, V₄, V₅, respectively, of these electrodes may be arranged to increase or decrease successively to provide a series of similar lenses.

Having now particularly described and ascertained the nature of my said invention and in what manner the same is to be performed, I declare that what I claim is:

1. An electrode system for forming an electron lens comprising two aligned co-operating electrodes affording an unobstructed passage for an electron beam to be acted upon, and having the inner edges of each electrode presented to the adjacent inner edges of the other of said electrodes, said edges being differently curved with respect to each other to provide a curved lens mid-plane, the curvature of said mid-plane being related to the shape of said electrodes to minimize spherical aberration in said lens.

2. An electrode system of the type described in claim 1 characterized in that said adjacent inner edges of said electrodes are concentrically curved.

3. An electrode system of the type described in claim 1 characterized in that said adjacent inner edges of said electrodes are complementarily curved and in registry.

4. An electrode system of the type described in claim 1 wherein each of said electrodes comprises a pair of parallel disposed plane elements disposed symmetrically on opposite sides of said passage, said adjacent inner edges of each of said pairs of said elements being curved to determine said mid-plane curvature.

5. An electrode system for forming an electron lens comprising two aligned co-operating electrodes affording an unobstructed passage for an electron beam and of which one electrode is of smaller diameter than the other and has one end inserted within the other, the edge of said inserted end of said smaller diameter electrode being curved to provide a curved lens mid-plane, the curvature of said mid-plane being related to the shape of said electrodes to minimize spherical aberration in said lens.

6. An electrode system of the type described in claim 1 wherein said electrodes are of cylindrical 20 tubular form.

7. An electrode system of the type described in claim 1 wherein said electrodes are of tubular form.

8. An electrode system for forming an electron lens comprising a pair of apertured diaphragm electrodes disposed with their apertures aligned to afford an unobstructed passage for an electron beam, said electrodes having their facing surfaces differently curved with respect to each other to provide a curved lens mid-plane, the curvature of said mid-plane being related to the shape of said electrodes to minimize spherical aberration in said lens.

9. An electrode system of the type described in claim 1 including means for applying focusing

potentials to said electrodes, and wherein said lens mid-plane curvature provides an electron image forming a line transverse to the axis of said electron beam.

10. An electrode system of the type described in claim 5 including means for applying focusing potentials to said electrodes, and wherein said lens mid-plane curvature provides an electron image forming a line transverse to the axis of said electron beam.

11. An electrode system of the type described in claim 8 including means for applying focusing potentials to said electrodes, and wherein said lens mid-plane curvature provides an electron image forming a line transverse to the axis of said electron beam.

12. An electrode system for forming a compound electron lens system comprising a plurality of aligned cooperating electrodes affording an unobstructed passage for an electron beam to be acted upon and having the inner edges of each electrode presented to the adjacent inner edges of another of said electrodes, said edges being differently curved with respect to each other to provide a curved lens mid-plane between each of said adjacent electrodes, the curvature of said mid-plane being related to the shape of said electrodes to minimize spherical aberration in said lens.

13. An electrode system of the type described in claim 12 including means for applying focusing potentials to said electrodes, and wherein said lens mid-plane curvature provides an electron image forming a line transverse to the axis of said electron beam.

OTTO ERNST HEINRICH KLEMPERER.
